SNAP HOOK

Leroy C. Doane, Meriden, Conn., assignor to The
Miller Company, Meriden, Conn., a corporation
of Connecticut

Application May 1, 1937, Serial No. 140,136

1 Claim. (Cl. 24—233)

The present invention relates to snap hooks and more particularly to hooks suitable for supporting the shade of an indirect lighting fixture.

The present invention contemplates snap hooks which can be made out of light weight sheet metal parts stamped and formed to shape, capable of easy assembly and of easy operation for securing and releasing the shade to be supported.

The accompanying drawing shows, for purposes of illustrating the present invention, an embodiment in which it may take form, it being understood that the drawing is illustrative of the invention rather than limiting the same. In the drawing:

Fig. 1 is a vertical sectional view of a lighting fixture, showing the parts in normal position;

Fig. 2 is a sectional view of the snap hook in the position of Fig. 1;

Fig. 3 is a sectional view of the latching member in release position;

Fig. 4 is a section on 4—4 of Fig. 2; and

Fig. 5 is a perspective of the latching member.

Referring to the drawing the socket cover 6 is provided with openings 7 through which shade supporting straps 8 pass, the straps being secured to a ring 9 of the cap extension member 10.

The lower ends of the straps 8 have a diagonal slot cut out therefrom terminating the strap in a hook 12 with an elongated shank 11, the inner wall 13 of the shank tapering toward the hook eye 14, and further provided with a hole 21 above the shank, this construction being preferred as the strap may be stamped from a single piece of metal to the form shown. The latching member 15 is preferably stamped out of a piece of resilient sheet metal, and has side walls 17 adapted to embrace the strap 8 and to be secured to it by a pin 23 which passes through holes 20 in the latching member and hole 21 in the strap 8. The lower end 16 of the latching member extends nearly to the point of the hook 12. A portion of the material of the latching member is formed into a spring 18 having an end 19 adapted to bear on the wall 13 of the slot or cutout and normally hold the latching member 15 in the position of Figure 2, the upper end 30 abutting the edge 22 of the strap.

The shade 24 is provided with supports including eye members 25. To position the shade the latching member 15 is pivoted inwardly against the tension of spring 18 (Fig. 3), whereupon the eye may be dropped through hook opening 14 into place. Leaf spring 18 will force the latching member outwardly, closing the opening whereby accidental dislodgement is prevented. With this construction one or two eyes may be removed from the hooks to permit cleaning of the inside of the shade and the remaining one will securely hold the shade in suspended position.

It is apparent that, within the scope of the invention, modifications and different arrangements may be made other than that herein disclosed, and the present disclosure is illustrative merely, the invention comprehending all variations thereof.

What is claimed is—

A snap hook comprising an elongated flat body member of generally rectangular cross section and having a hole spaced from the end and a diagonally disposed slot extending from adjacent the hole nearly to the end to form a hook with a point facing the hole, a latching member in the form of a piece of resilient sheet metal of channel shaped cross section embracing the body member, the latching member having aligned holes, a pivot pin passing through the holes in the latching member and in the body member, the point of the hook being spaced slightly beyond the end of the latching member so that the latching member may swing transversely across the slot to admit a device into the slot, a portion of the latching member being bent inwardly toward the wall of the slot and providing a spring which bears on said slot wall and urges the end of the latching member outwardly to be close to the end of the hook to prevent removal of the device, the other end of the latching member engaging the body member to stop the latching member in said outer position.

LEROY C. DOANE.
